UNITED STATES PATENT OFFICE.

MAUDE BLANCHE FRYE, OF BOSTON, MASSACHUSETTS.

DESIGN FOR A SPOON.

SPECIFICATION forming part of Design No. 22,546, dated June 20, 1893.

Application filed April 27, 1893. Serial No. 472,131. Term of patent 3½ years.

To all whom it may concern:

Be it known that I, MAUDE BLANCHE FRYE, a citizen of the United States, residing at Boston, in the county of Suffolk and State of Massachusetts, have invented and produced a new original Design for a Spoon, of which the following is a specification, reference being had to the accompanying drawings, illustrating my design, in which—

Figure 1 is a front view of a spoon showing my design. Fig. 2 is an edge view of the same, and Fig. 3 is a back view, these three views being deemed necessary to fully illustrate my design.

The leading features of my design consist in the bowl and handle of a spoon having ornamental emblems of Harvard College as shown. The bowl of the spoon bears upon its front or concave surface a representation in low relief of the statue of John Harvard, the founder of Harvard College, surrounded by bead-work substantially parallel with the edge of the bowl. The handle of the spoon, the shank portion of which is flat and narrow with parallel sides, is embellished upon its front and rear surfaces with bead ornamentation having at the center a raised ro-

sette as shown. The end or head portion of the handle, which is of substantially circular form, bears upon its front surface a representation in low relief of a shield bearing devices emblematical of Harvard College, with the upper portion worked in crimson enamel, and upon the opposite surface of this circular end or head is a panel C, surrounded by a circle of small scrolls, the handle terminating in a substantially triangular shaped scroll ornamentation. At the junction of the handle with the back of the bowl is a scroll ornamentation as shown in Fig. 3, and both sides of the handle at the junction of the shank portion with the circular head have a scroll ornamentation, as shown in Figs. 1 and 3.

What I claim as new, and desire to secure by Letters Patent, is—

The design for a spoon, substantially as herein shown and described.

Witness my hand this 14th day of April, A. D. 1893.

MAUDE BLANCHE FRYE.

In presence of—

P. E. TESCHEMACHER,
FRANK L. CREEZY.
